(57) **CLAIM**

The ornamental design for a pet bowl stand, as shown and described.

DESCRIPTION

The patent or application file contains at least one drawing executed in color. Copies of this patent or patent application publication with color drawing(s) will be provided by the Office upon request and payment of the necessary fee.

1. Pet bowl stand

The design is a wooden pet bowl stand with four removable ball-shaped accessories on the base to adjust the angle of the bowl;

Fig. 1.1 is a front view of a pet bowl stand showing our new design;

Fig. 1.2 is a back view thereof;

Fig. 1.3 is a left view thereof;

Fig. 1.4 is a right view thereof;

Fig. 1.5 is a top view thereof;

Fig. 1.6 is a bottom view thereof;

Fig. 1.7 is a three quarter view thereof.
